UNITED STATES PATENT OFFICE.

GEORGE S. SPREYER, OF CANON CITY, COLORADO.

ATTACHMENT FOR VEHICLE-SPRINGS.

1,015,649.

Specification of Letters Patent.

Patented Jan. 23, 1912.

Application filed April 16, 1910. Serial No. 555,806.

To all whom it may concern:

Be it known that I, GEORGE S. SPREYER, a citizen of the United States, residing at Canon City, in the county of Fremont and State of Colorado, have invented new and useful Improvements in Attachments for Vehicle-Springs, of which the following is a specification.

This invention relates to improvements in attachments for vehicle springs and more particularly to the type known as elliptical springs.

One object of the invention is the provision of a device which may be permanently associated with the spring and perform the function of an auxiliary spring.

Another object is the provision of a device which may be employed for repairing a broken spring, the device being so constructed that it may be secured adjacent to the break in a spring and when so positioned will couple the broken sections together and by virtue of its construction, a broken spring body to which the device is applied will suffer no loss of resiliency.

With these and other objects in view, which will more fully hereinafter appear, the present invention consists in certain novel details of construction and arrangement of parts, hereinafter fully described, illustrated in the accompanying drawings and more particularly pointed out in the appended claim.

In the accompanying drawings, forming a part of the specification; Fig. 1 is a side elevation of a portion of the medial portion of a semi-elliptical spring with my improved device applied thereto. Fig. 2 is a plan view of the device as shown in Fig. 1. Fig. 3 is a detail side elevation of the device removed from the position shown in Figs. 1 and 2. Fig. 4 is a side elevation of one end portion of a vehicle spring after the same has been broken at the clip and showing my improved device in side elevation and applied to the clip and spring. Fig. 5 is a modified form of a repair device, employed for connecting the sections to a full elliptical spring. Fig. 6 is an end view of the same.

Similar numerals of reference are employed to designate corresponding parts throughout.

As shown in Fig. 1 the vehicle spring to which my device is applied comprises a plurality of leaves designated by the numeral 5,

the said spring being connected to an axle 6 by means of the usual axle clips 7. The auxiliary spring device forming the subject matter of the present invention comprises 60 a plurality of superimposed and substantially semi-elliptical leaves designated by the numeral 8. The leaves 8 are substantially of the same length and are fixedly secured together at their medial portions by 65 means of a bolt or rivet 9 passing through alining openings formed in the leaves. The device thus formed will be considerably less in length than the length of a semi-elliptical spring; as clearly shown in the drawings. 70

It will be observed by reference to Fig. 3 that the opposite ends of the leaves 8 are normally spaced from each other a slight distance so that when the ends are clamped together upon the vehicle spring, the said 75 leaf ends will form resilient and yielding auxiliary spring ends, whereby when the auxiliary spring is clamped in position upon the broken vehicle spring, the original resiliency and supporting strength will 80 be restored thereto.

The uppermost leaf in the device terminates at one end in an upturned extension 10, and at its opposite end terminates in an eye 11, the said eye 11 extending beyond the 85 adjacent ends of the leaves 8.

When the device is employed to repair a semi-elliptical spring broken at its medial portion, as shown in Fig. 1, the device is arranged on the concaved surface of the 90 spring 5 and so arranged that its curve will extend reversely to the curve of the spring 5. The device is adjusted to straddle the broken prong of the spring and when properly positioned is secured in place by 95 clamping devices which in the present instance are shown to include plates 12 and 13 of greater length than the widths of the device and spring 5 to which it is applied. The plates 13 are arranged transverse the 100 convex surface of the spring 5 and on either side of the break thereof and in alinement with the opposite end portions of the device, while the plates 12 are arranged transverse the device adjacent to its opposite ends, as 105 shown in Fig. 1. The opposite end portions of the plates 12 and 13 are provided with openings for the reception of bolts 14 inserible through the openings, the said bolts being provided at one end with heads 15 to 110 bear on the plates 12, while their opposite end portions are threaded to receive nuts

16 to bear on the lower faces of the plates 13. With this construction it will be manifest that by turning the nuts 16 after the bolts have been positioned that the device 5 and spring 5 will be firmly clamped between the plates 12 and 13.

In positioning the plates on the device one of said plates is arranged to bear on the inner surface of the extension 10, while the plate at the opposite end is positioned adjacent to the eye 11. It will be manifest, owing to the leaves being secured only at their medial portions that the resiliency of the device will be increased over a structure in which the leaves 8 were welded together throughout their lengths or if the device were formed of a single piece of metal corresponding in dimensions to the combined lengths, widths and thicknesses of the leaves 8. Thus it will be seen that a spring repaired with the device will lose none of its resiliency, in fact the device may be permanently applied, as shown in Fig. 1, to an unbroken spring wherein it will 25 act as a supplemental spring.

As shown in Fig. 4 the device is applied to a semi-elliptical spring broken off at the hanger 17. In this instance the hanger bolt 18 is passed through the eye 11 at one 30 end of the device, while the opposite end portion is clamped to the spring body by bolts 19 and plates 20 and 21, in the manner before described. It is to be noted that in this instance the weight of the vehicle body will force the eyed end of the upper leaf downwardly causing the terminal ends of all the leaves to move in close engagement with each other, thus forming a spring end equal to the original.

40 In Figs. 5 and 6 I have shown a modified form of the device employed for repairing a break in a full elliptical spring when the said break occurs at either end of said

spring. In this connection I employ a pair of straps designated by the numerals 22 and 45 23 the said straps being offset at their medial portions, the spaces between the opposite ends of the straps will be different when the straps are united by bolts 24. One of the bolts 24 is adapted to be inserted 50 through the opening at the end of one side of the spring, while the opposite bolt receives the eye 11 of the device, the latter being secured to the opposite side of the spring in the manner before described. 55

From the foregoing, it is evident that I have provided a device which is comparatively simple in structure and inexpensive in manufacture, embodying few parts and these so arranged that the danger of derangement will be reduced to a minimum. 60

I claim:—

A device for repairing elliptical springs including an auxiliary spring consisting of a plurality of superimposed semi-elliptical leaves of a corresponding length and shorter than the said vehicle spring, the said leaves loosely bearing one upon the other and riveted together at their central portions, the terminal portions of the leaves being normally spaced apart so that when clamped together they form a resilient spring end, the upper of said leaves terminating at one end in an upturned extension and provided at its opposite end with an eye, and means adapted 70 to bear on the upturned extension and passing through the eye for securing the ends of the auxiliary spring on opposite sides of the line of cleavage in the vehicle spring. 75

In testimony whereof I affix my signature in presence of two witnesses.

GEORGE S. SPREYER.
